UNITED STATES PATENT OFFICE.

WILLIAM SNOW, OF DETROIT, MICHIGAN.

DESIGN FOR IRON FENCE.

Specification forming part of Design No. **7,486**, dated June 9, 1874; application filed May 9, 1874.
[Term of Patent 7 years.]

To all whom it may concern:

Be it known that I, WILLIAM SNOW, of Detroit, in the county of Wayne and State of Michigan, have invented a new and original Design for an Iron Fence, of which the following is a specification:

The nature of my design is fully represented in the accompanying photographic illustration, to which reference is made.

The said design consists of the double coil of the wires or rods on the top rail.

I claim as my invention—

The design for an iron fence, substantially as shown and set forth.

WM. SNOW.
